TURNSTILE ANTENNA

Nathan W. Aram, Chicago, Ill., assignor to
Zenith Radio Corporation, Chicago, Ill., a corporation of Illinois

Application July 2, 1942, Serial No. 449,437

34 Claims. (CL 250—33)

This invention relates to turnstile antennas particularly intended for the radiation of ultra high frequency energy.

One of the objects of the present invention is to provide an improved turnstile antenna.

A further object of the invention is to provide an improved feeder and phasing system for turnstile antennas.

A further object of the invention is to provide a practical turnstile antenna in which the feed lines are properly matched by the radiating elements.

A further object of the invention is to provide a practical turnstile antenna in which the power is equally divided between the radiating elements at various levels.

A further object of the invention is to provide a practical turnstile antenna in which the feeding of a multiplicity of radiating elements in proper phase is effected without twisting or spiraling feed lines around the mast.

A further object of the invention is to provide a turnstile antenna which can be installed without difficult and tedious impedance matching adjustments during installation.

A further object of the invention is to provide a practical turnstile antenna in which many of the phasing elements and connections of the feeder system may be placed below the level of the mast and inside a building.

Other objects, advantages and capabilities will appear from the following description of a preferred embodiment thereof taken in conjunction with the accompanying drawings, in which:

Figure 1 is a perspective view of an improved turnstile antenna embodying my invention;

Fig. 2 is an expanded diagrammatic view showing the dipole elements of the turnstile antenna shown in Fig. 1 and the feeder system including the phasing and impedance matching elements thereof, the outer conductor being omitted from some of the co-axial lines for the purpose of clarity;

Fig. 3 is a sectional plan view taken on the line 3—3 of Fig. 1 showing the lowermost level of the turnstile antenna in plan view;

Fig. 4 is a similar plan view taken on the line 4—4 of Fig. 1 showing the dipoles of the second level from the bottom in plan view;

Fig. 5 is a sectional detail showing the manner in which any vertical coaxial line of the antenna is connected to any dipole element on the bays other than the uppermost two bays; and

Fig. 6 is a similar sectional detail view show-

ing the manner in which any vertical coaxial line of the antenna is connected to any dipole element of the uppermost two bays.

Referring to the drawings, my improved turnstile antenna is preferably mounted upon a metal mast 10 which is grounded. Since the field strength existing at any given receiving point is proportional to the height of the transmitting antenna, the mast 10 is preferably at the highest position available. This is normally on the top of one of the highest buildings in a city.

The radiating elements of my improved antenna are folded dipoles. Folded dipoles consist of a plurality of parallel, close-spaced conductors connected together in series. A common form of folded dipole comprises a conductor of approximately half a wave length, two return bends at the ends thereof, and two portions which extend inwardly therefrom to points of termination adjacent the center of the major length of the dipole. The center of this major length of the dipole is a voltage zero and may be grounded. Consequently, in my antenna this major length is in two parts each of which is conductively secured to diametrically opposed points on the mast 10.

Furthermore, in this common form of folded dipole the return bends are oppositely directed so that the two minor portions are normally located on one side of the major portion. My improved antenna embodies a type of dipole in which the return bends are in the same direction, that is, both clockwise or both counterclockwise, so that the minor portions of the dipole lie on opposite sides of the major portion of the dipole. As will hereinafter appear, this modification facilitates the connection of the feeder system to the dipoles.

A turnstile antenna may comprise a plurality of bays or levels mounted on the mast and having a spacing of half a wave length. Each level or bay normally comprises two dipoles at right angles to each other. All the dipoles in one panel, that is, the dipoles having one direction, for example, north and south in one case, and east and west in the other case, are excited in phase, and the dipoles of one direction, north and south, for example, are excited out of phase by ninety degrees from the dipoles of the other direction, east and west, for instance. With this ninety-degree relationship, the radiation pattern is substantially circular. Radiation is concentrated towards the horizontal direction as a function of the number of levels with radiating elements in the same phase.

For convenience of reference, I will refer to the various dipoles as N2—S2, W3—E3, etc., these indicia meaning the second dipole from the bottom lying in the north and south direction and the third dipole from the bottom lying in the west and east direction. Similarly, I find it convenient to refer to the individual radiating elements as N2, E3, S4, etc. It is to be noted, however, that this nomenclature is for ease of reference only. Since the radiated pattern is substantially circular, the points of the compass to which the dipoles are directed have no effect and it is to be understood that the antenna as a whole can be considered to be rotated from its position through any number of degrees without any change of effect.

I have previously pointed out that each of my dipoles has return bends directed in the same direction. I prefer to make this direction the same at any one bay or level and to alternate the direction for each bay or level along the mast.

Thus, referring to Fig. 3, which shows in plan the dipole elements of the lowermost bay or level, it is to be noted that the return bends are in the counterclockwise direction, whereas in Fig. 4 which is a corresponding view of the second bay or level, the return bends are in the clockwise direction. Indeed, all the odd numbered bays, counting from the bottom, follow the pattern of Fig. 3, and all the even numbered bays, counting from the bottom, follow the pattern of Fig. 4.

It will therefore be understood that the free ends of the radiating elements N1, N3, etc., are in vertical alignment, so that they may be fed by a feeder line 11 which extends upwardly along the mast 10. This feeder line is located between the N and W elements, being more adjacent the N elements. The N2, N4, etc., elements have their free ends between the N and E elements and nearer the N elements, and they are arranged to be fed by a line 12.

The W2, W4 elements are fed by a line 13, the W1, W3 elements, etc., being fed by a line 14. The S1, S3 elements are fed by a line 15, the S2, S4, etc., elements being fed by a line 16. The E2, E4 elements are fed by a line 17, the E1, E3 elements, etc., being fed by a line 18.

By reference to Fig. 3 or 4, it will be seen that the feeder lines constitute a circumferential series around the mast 10 in the following order: 11, 12, 18, 17, 15, 16, 14 and 13. It is to be noted that 11 and 12 are adjacent the N elements on opposite sides thereof, that 17 and 18 are adjacent the E elements and on opposite sides thereof, that 15 and 16 are adjacent the S elements and on opposite sides thereof, and that 13 and 14 are adjacent the W elements and on opposite sides thereof. This enables all these feeder lines to extend vertically upwards along the mast 10 and without any crossing of feeder lines.

Since each of these feeder lines is connected to alternate dipoles in the longitudinal direction of the mast, and since these alternate dipoles are one wave length apart, each feeder line, in the embodiment of the invention illustrated, feeds two dipoles in phase. All circuit elements for correct phasing and impedance matching other than those inherent in the folded dipoles and the feeder lines on the mast themselves, are located at a convenient level below the radiating elements as will hereinafter be described.

The feeder lines 11, 12, 13, 14, 15, 16, 17 and 18 are preferably coaxial lines, the various dipole elements being connected to the inner conductor of the coaxial lines through dielectric bushings

19 in suitable fittings 20 and 20' (Figs. 5 and 6). The lines 11 and 15 are connected to the lines 12 and 16, respectively, at points 21 and 22, at a position below the dipole elements and preferably 5 below the mast 10.

In order that all the N—S dipoles should be excited in phase, the distances of any two N—S dipoles from the points of connection 21 and 22 must either be equal or different from each 10 other by an integral number of wave lengths. This may readily be attained as shown in Fig. 2 by making the lengths of the coaxial lines between N1—S1 and N2—S2 and the points of the connections 21 and 22 equal. Since N1—S1 and 15 N2—S2 are at different elevations, the correct distances between them and the common points 21, 22 can conveniently be attained by providing loops in the lines 11 and 15.

In order that all the W—E dipoles may be in 20 phase, the coaxial lines 13 and 17 and the coaxial lines 14 and 18, respectively, are connected together at points 23 and 24, respectively. The points 21, 22, 23 and 24 are preferably at the same level. Here again, in order that all the 25 W—E dipoles may be in phase, the distances from all of the W—E dipoles to the points 23 and 24 should be equal or should differ from each other by an integral number of wave lengths. This may be attained as shown in Fig. 2 by making 30 the length of the coaxial lines between W2—E2 and the points 23 and 24, the same length as the coaxial lines between W1—E1 and the points 23 and 24.

It has previously been pointed out that there 35 should be a phase difference of 90° between the dipoles of the two different directions. This may be accomplished by using a quarter wave connecting line 25 between point 21 and point 23 and a quarter wave connecting line 26 between point 40 22 and point 24. It should be understood that these quarter wave lines may be transposed so that one of them connects the point 21 to the point 24 and the other connects the point 22 to the point 23 and still produce a correct phase 45 relation between the N—S panel and the E—W panel. This reversal of connection merely reverses the direction of rotation of the field surrounding the antenna. Correct phase relationship between the two panels can be attained by 50 employing coaxial connecting lines 25 and 26 between the points 21 and 22, and 23 and 24, of three-quarters of a wave length, or indeed any other odd number of quarters of wave lengths. In practice, it is preferred to make these connecting 55 lines one quarter of a wave length.

Energy is supplied to the points 21 and 22 by means of coaxial lines 27 and 28 which convey signal from the transmitter. The lines 27 and 60 28 are connected to the points 21 and 22 by means of quarter wave length coaxial line transformers 29 and 30, which are connected directly to the points 21 and 22. The quarter wave lengths 29 and 30 have a surge impedance, determined by 65 the ratio of the outer diameter of the inside conductor and the inner diameter of the outside conductor, which is the geometric mean of the surge impedance of the lines 27 and 28 and the parallel impedance of all radiating elements measured at the points 21 and 22. Thus, the impedance of 70 the radiating system is perfectly matched to the impedance of the lines 27 and 28. Normally, I prefer to keep the outer conductor of the quarter wave length sections 29 and 30 the same as that of the coaxial lines 27 and 28 and the variation 75 of surge impedance can readily be attained by

simply varying the external diameter of the inner conductors of the quarter wave sections 29 and 30. It is known that the surge impedance of a coaxial line is

$$138 \log_{10} \frac{d_1}{d_2}$$

where d_1 and d_2 are the internal diameter of the outer conductor and the external diameter of the inner conductor, respectively. Consequently, it will readily be understood that by varying d_2 of the quarter wave sections 29 and 30, perfect impedance matching can be attained.

It should be noted that a major advantage of this invention is that the circuit permits not only perfect impedance matching between the lines 27 and 28 and the feed points 21 and 22, but also provides perfect impedance matching between the vertical lines on the mast and the radiator elements taken in pairs. This can best be understood by tracing the impedance relations through the circuit of the embodiment of the invention just described. For example, the terminal impedances of the individual dipoles are chosen to be 280 ohms. Thus, at N4—S4, the impedance across the two lines 12 and 16 is 280 ohms. This impedance, viewed at the terminal points of N2—S2, one wave length away, is also 280 ohms. This impedance, in parallel with the 280 ohm impedance of N2—S2, provides an impedance of 140 ohms between the lines 12 and 16 at the points of connection with N2—S2. Since equal resistive impedances are connected in parallel, equal power division is obtained between N2—S2 and N4—S4.

The coaxial lines 12 and 16 are, for this embodiment, standard 70-ohm transmission lines which exactly match the 140-ohm impedance appearing across the connecting points of N2—S2 and they can extend down to the points 21 and 22 for any practical length so that these points and the quarter wave transformers 29 and 30 may be located in any suitable building below the mast.

The relationship between the other pair of dipoles N3—S3 and N1—S1 to the points 21 and 22 is precisely similar. Consequently, equal power division exists between the two pairs of lines 12, 16 and 11, 15 respectively. A similar relationship with regard to impedance and distribution of power exists between the dipoles W4—E4 and W2—E2, and the dipoles W3—E3 and W1—E1 and the points 23 and 24.

The relationship between the other pair of 21 and 22 is one fourth of 280 ohms, or 70 ohms; likewise, the net impedance at the points 23 and 24 is 70 ohms. The quarter wave lines 25 and 26 which connect the points 21 and 22 to 23 and 24 have a surge impedance of 70 ohms so that they are properly terminated at the points 23 and 24. Each of the lines 25 and 26 has a surge impedance of 35 ohms. Therefore, at the feed points 21, 22, equal 70-ohm impedances are parallel, and equal power division exists between all the dipoles.

A folded dipole can very readily be made with a terminal impedance of 280 ohms. Consequently, I am able to employ as my vertical lines, standard coaxial lines having an impedance of 70 ohms and to obtain, in the manner described above, equal distribution of power among all the dipoles. Furthermore, all the phasing and matching connections other than those inherent in the lines themselves can be located below the mast and at any suitable position.

It will, of course, be understood that I do not intend to be limited to a turnstile antenna having four levels or bays. I can have any other number

of levels with suitable adjustment of the terminal impedances of the dipoles employed and/or the surge impedance of the vertical lines. Thus, if I desire to increase the number of bays to six, I may employ dipoles having impedances of 420 ohms and I may connect them in threes with standard 70-ohm coaxial lines in the same manner as the dipoles are connected in pairs in the embodiment of the invention described above.

- 10 In the embodiment of the invention described in detail above, there is a slight mismatch between the 70-ohm coaxial lines 11 and 15, for example between the points of connection N1—S1 and N3—S3. This slight mismatching may be corrected by employing coaxial lines, between the points of connection of the dipoles thereto, of appropriate surge impedance perfectly to match the impedance of the upper dipole. Thus, in the embodiment specifically described in connection with Fig. 2, I may make the coaxial lines between N1—S1 and N3—S3 of 140-ohms surge impedance so that they precisely match the impedance of 280 ohms of the N3—S3 dipole. Similarly, the corresponding portions of the coaxial lines 12 and 16, 13 and 17, and 14 and 18 could be 140 ohms. With this modification, all the dipole impedances are perfectly matched and there are no standing waves on any part of the feeder system. In case more than four bays are embodied in the antenna, 30 it is obvious that the same result may be obtained by using for the vertical feeder lines 11, 15, etc., coaxial lines having appropriate different surge impedances in the portions between the dipoles at which these lines are connected.

35 My improved antenna is broadly resonant and is therefore well adapted for the purposes of frequency modulation transmission and the transmission of television and similar signals.

It is to be noted that all the outer conductors 40 of the coaxial lines are grounded and consequently the outer conductors of the coaxial lines 11 to 18 extending along the mast 16, are anchored directly to the mast, for example by cleats. One simple method of securing them may 45 be by means of metal straps 31 which extend around these conductors, the straps being tight enough to hold the coaxial lines up against the outside of the mast, particularly adjacent the radiating elements effectively to ground the outer conductors to the mast at these points.

50 My improved antenna is ordinarily employed with the mast vertical and for convenience of description, an antenna with a vertical mast has been described herein. It is to be noted, however, that for certain purposes the mast and the antenna as a whole may be tilted out of the vertical direction. Thus, I may locate the mast and the antenna as a whole in a horizontal direction in which case I will radiate energy principally in 55 an elongated zone. Thus, with a horizontal mast directed east and west, I will have substantially no radiation in the east and west direction and strong radiation in the north and south direction and in directions close thereto. The radiation in this case will, of course, be directed also in an upward direction and in generally upward directions.

60 Although the invention has been described in connection with specific details of a preferred embodiment thereof, it must be understood that such details are not intended to be limitative of the invention except in so far as set forth in the accompanying claims.

65 I claim:

70 1. In a turnstile antenna, in combination, a

pair of crossed folded dipoles at each of a plurality of spaced planes, each folded dipole comprising a major length, two return bends and two inwardly directed lesser lengths, all return bends of one plane being directed in the clockwise direction and all return bends of an adjacent plane being directed in the counterclockwise direction.

2. In a turnstile antenna, in combination, a pair of crossed folded dipoles at each of a plurality of spaced planes, each folded dipole comprising a major length, two return bends and two inwardly directed lesser lengths, all bends at each plane being directed in the same direction and all bends at successive planes being directed in alternating clockwise and counterclockwise directions, and a plurality of straight feeder lines connected to said lesser lengths, each feeder line being connected only to corresponding lesser lengths of alternate planes.

3. In an antenna, in combination, a plurality of dipoles at a plurality of planes and located approximately half a wave length apart in the longitudinal direction and located in a longitudinal panel, and a feeder system comprising two straight feeder lines connected to similar points of one set of alternate dipoles of said panel and another pair of straight feeder lines connected to similar points of the other alternate dipoles of said panel.

4. A turnstile antenna having a pair of crossed dipoles at each of a plurality of spaced planes, the dipoles being directed so as to provide four sets of radial radiating elements directed in four different directions, said dipoles comprising a major length, return bends at the ends thereof, and lesser lengths extending inwardly from said return bends, all return bends at the ends of the radial radiating elements of each plane being in one direction, said direction being alternately clockwise and counterclockwise along the series of planes.

5. A turnstile antenna having a pair of crossed dipoles at each of a plurality of spaced planes, the dipoles being directed so as to provide four sets of radial radiating elements directed in four different directions, said dipoles comprising a major length, return bends at the ends thereof, and lesser lengths extending inwardly from said return bends, all return bends at the ends of the radial radiating elements of each plane being in one direction, said direction being alternately clockwise and counterclockwise along the series of planes, and a pair of straight feeder lines for each set of elements directed in one direction, one of said feeder lines being connected to the innermost ends of the lesser portions of alternate radiating elements of one set and the other feeder line being connected to the other alternate elements of said set.

6. A turnstile antenna comprising a mast, dipoles in crossed relation at a plurality of spaced planes on said mast and located approximately half a wave length apart in the longitudinal direction and providing four aligned series of radial radiating elements directed in four different directions from the mast, a straight feeder system comprising a feeder line connected only to one set of alternate elements of one series and another feeder line connected only to the other alternate set of said elements of said series, said feeder lines being connected together in such manner that the distances of any two elements of said series from the point of connection of said feeder lines are equal or differ by an integral

number of wave lengths whereby all of said radiating elements are excited in phase.

7. A turnstile antenna comprising a mast, dipoles in crossed relation at a plurality of spaced planes on said mast and located approximately half a wave length apart in the longitudinal direction and providing four series of radial radiating elements directed in four different directions from the mast, a feeder system comprising four pairs of straight feeder lines, one pair being associated with a series of radial radiating elements, one of said pair being connected only to one set of alternate elements of said series and the other feeder line of said pair being connected only to the other alternate set of said elements of said series, the feeder lines of each pair being connected together in such manner that the distances of any two elements of one series from the point of connection between its associated feeder lines is equal or differs by an integral number of wave lengths, whereby all of said radiating elements of each series are excited in phase.

8. A turnstile antenna comprising a panel of dipoles in parallel longitudinally spaced relation, a second similar panel having its dipoles at right angles to the dipoles of the first said panel, each panel comprising a plurality of sets of dipoles spaced from each other by one wave length, and a plurality of straight feeder lines, each line being connected only to one of said sets.

9. A turnstile antenna comprising a panel of dipoles in parallel longitudinally spaced relation, a second similar panel having its dipoles at right angles to the dipoles of the first said panel, each panel comprising a plurality of sets of dipoles spaced from each other by one wave length, a plurality of straight feeder lines, each line being connected only to one of said sets, and phasing connections between said feeder lines below said dipole elements.

10. A turnstile antenna comprising a panel of dipoles in parallel longitudinally spaced relation, a second similar panel having its dipoles at right angles to the dipoles of the first said panel, each set comprising a plurality of dipoles spaced from each other by one-half wave length, and a plurality of straight feeder lines, each line being connected only to a plurality of similar points on dipoles separated from each other by one wave length.

11. A turnstile antenna comprising a panel of dipoles in parallel longitudinally spaced relation, a second similar panel having its dipoles at right angles to the dipoles of the first said panel, the dipoles of each panel being spaced one from the other by one-half wave length, four straight feeder lines, each feeder line being connected only to the alternate dipoles of one panel, each pair of feeder lines of each panel being connected together to excite the dipoles of each panel in phase, a main feeder line connected to one of the points of connection, and a feeder line of an odd number of quarter wave lengths connecting said points of connection whereby said panels are excited in phase quadrature.

12. In a turnstile antenna, in combination, a plurality of dipoles in crossed relation at a plurality of planes and located approximately half a wave length apart in the longitudinal direction and providing four longitudinal series of radial radiating elements directed in four different directions, and a feeder system comprising a

straight feeder line connected only to similar points of one set of alternate elements of one series and another straight feeder line connected to similar points of the other alternate elements of said series, said feeder lines being coaxial lines, the inner conductor thereof being connected to the dipoles.

13. A turnstile antenna having a pair of crossed dipoles each at a plurality of spaced planes, the dipoles being directed so as to provide four sets of radial radiating elements directed in four different directions, said dipoles comprising a major length, return bends at the ends thereof, and lesser lengths extending inwardly from said return bends, all return bends at the ends of the radiating elements being directed in one direction at each plane, said direction being alternately clockwise and counterclockwise at successive planes along the series of planes, and a pair of straight feeder lines for each series of elements directed in one direction, one of said feeder lines being connected only to the innermost ends of the lesser portions of one alternate set of radiating elements of one series and the other feeder line being connected only to the other alternate set of said series, said feeder lines being constituted by coaxial lines the inner conductors whereof are connected to the dipoles.

14. A turnstile antenna having a pair of crossed dipoles each at a plurality of spaced planes arranged in two longitudinal panels, the dipoles being directed so as to provide four sets of radial radiating elements directed in four different directions, said dipoles comprising a major length, return bends at the ends thereof, and lesser lengths extending inwardly from said return bends, all return bends at the ends of the radial radiating elements being directed in one direction at each plane, said direction being alternately clockwise and counterclockwise along the series of planes, a pair of straight feeder lines for each series of elements directed in one direction, one of each pair of feeder lines being connected only to the innermost ends of the lesser portions of one alternate set of radiating elements of one series and the other feeder line of said pair being connected only to the other alternate set of said series, said feeder lines being constituted by coaxial lines the inner conductors whereof are connected to the dipoles, the feeder lines of each pair being connected together at points of connection to supply their elements in phase, main feeder coaxial lines excited in opposite phase connected to the points of connection of one panel, and coaxial lines of an odd number of quarter wave lengths connecting the points of connection of one panel to the points of connection of the other panel, whereby all the dipoles of each panel are excited in phase and all the dipoles of the two panels are excited in phase quadrature.

15. A turnstile antenna comprising a mast, dipoles in crossed relationship at a plurality of planes on said mast and located approximately half a wave length apart in the longitudinal direction and providing four longitudinal series of radial radiating elements directed in four different directions from the mast, a feeder system comprising a coaxial feeder line connected only to one set of alternate elements of one vertical series and another coaxial feeder line connected only to the other alternate set of said elements of said series, said coaxial feeder lines being connected together in such manner that the distances

of any two elements of said series from the point of connection between its two feeder lines are equal or differ by an integral number of wave lengths whereby all of said radiating elements are excited in phase.

16. A turnstile antenna comprising a mast, dipoles in crossed relationship at a plurality of spaced planes on said mast and located approximately half a wave length apart in the longitudinal direction and providing four longitudinal series of radial radiating elements directed in four different directions from the mast, a feeder system comprising four pairs of straight coaxial feeder lines, one pair being associated with a longitudinal series of radial radiating elements, one of said pair being connected only to one set of alternate elements of said series and the other feeder line of said pair being connected only to the other alternate set of said elements of said series, each pair of said coaxial feeder lines being connected together in such manner that the distances of any two elements of one series from the point of connection between its two feeder lines are equal or differ by an integral number of wave lengths, whereby all of said radiating elements of each series are excited in phase.

17. A turnstile antenna comprising a panel of dipoles in parallel longitudinally spaced relation, a second similar panel having its dipoles at right angles to the dipoles of the first said panel, each panel comprising a plurality of sets of dipoles spaced from each other by one wave length, and a plurality of straight coaxial feeder lines, the inner conductor of each line being connected only to one of said sets.

18. A turnstile antenna comprising a panel of dipoles in parallel longitudinally spaced relation, a second similar panel having its dipoles at right angles to the dipoles of the first said panel, each panel comprising a plurality of dipoles spaced from each other by one-half wave length, and a plurality of straight coaxial feeder lines, each line being connected only to a plurality of similar points on dipoles separated from each other by one wave length.

19. A turnstile antenna comprising a panel of dipoles in parallel longitudinally spaced relation, a second similar panel having its dipoles at right angles to the dipoles of the first said panel, each panel comprising a plurality of dipoles spaced from each other by one-half wave length, a plurality of straight coaxial feeder lines, each line being connected only to a plurality of similar points on dipoles separated from each other by one wave length, a pair of main coaxial feeder lines, a feeder connecting system connecting the straight coaxial feeder lines for similar ends of one panel and similar ends of another panel to one main feeder line, another feeder connecting system connecting the straight coaxial feeder lines for the other ends of both said panels to the other main coaxial feeder line, said feeder connecting systems comprising coaxial lines of such length to feed opposite ends of said dipoles with 180° phase difference, to feed all dipoles of each panel in phase, and to feed one panel with a phase of 90° ahead of the other panel.

20. A turnstile antenna comprising a panel of dipoles in parallel longitudinally spaced relation, a second similar panel having its dipoles at right angles to the dipoles of the first said panel, the dipoles of each panel being spaced one from the other by one-half wave length, eight straight feeder lines, each feeder line being connected only

to similar ends of alternate dipoles of one panel, the pair of feeder lines connected to similar ends of the dipoles of one panel being connected together to excite the dipoles of the panel in phase, a pair of main feeder lines excited in opposite phase, connected to the points of connection of the feeder lines of one panel, and feeder lines of an odd number of quarter wave lengths connecting the points of connection of one panel to the points of connection of the other panel whereby each panel is excited in phase and the two panels are excited in phase quadrature.

21. In a turnstile antenna, in combination, a plurality of folded dipoles in longitudinally spaced and aligned relation, the spacing being one wave length, and a pair of straight coaxial feeder lines the inner conductor of one line being connected only to aligned ends of the dipoles and the inner conductor of the other line being connected only to the other aligned ends of the dipoles, the surge impedances of the lines being arranged to match the parallel impedances of the dipoles.

22. In a turnstile antenna, in combination, a plurality of folded dipoles in spaced and aligned relation, the spacing being one wave length, and a pair of straight coaxial feeder lines the inner conductor of one line being connected only to aligned ends of the dipoles and the inner conductor of the other line being connected only to the other aligned ends of the dipoles, the surge impedances of the lines below the dipoles being arranged to match the parallel impedances of the dipoles, and the surge impedances of the portions of the lines between two dipoles being arranged to match the parallel impedances of the dipoles above said portions.

23. In a turnstile antenna, in combination, a plurality of folded dipoles arranged in crossed relation in two longitudinal panels, the dipoles being spaced apart half a wave length, a plurality of coaxial feeder lines, each feeder line having its inner conductor connected only to similar ends of alternate dipoles of a panel, each pair of coaxial feeder lines thus connected to similar ends of the dipoles of a panel being connected together at points of connection to feed said similar ends in phase, a pair of main feeder coaxial lines of opposite phase connected to the points of connection of one panel and coaxial lines of an odd number of quarter wave lengths connecting the points of connection of one panel to the points of connection of the other panel, the surge impedances of the first said feeder lines connected to one alternate set of dipoles of one panel being arranged to match the parallel impedances of the dipoles to which they are connected.

24. In a turnstile antenna, in combination, a plurality of folded dipoles arranged in crossed relation in two longitudinal panels, the dipoles being spaced apart half a wave length, a plurality of coaxial feeder lines, each feeder line having its inner conductor connected only to similar ends of alternate dipoles of a panel, each pair of coaxial feeder lines thus connected to similar ends of the dipoles of a panel being connected together at points of connection to feed said similar ends in phase, a pair of main feeder coaxial lines of opposite phase connected to the points of connection of one panel and coaxial lines of an odd number of quarter wave lengths connecting the points of connection of one panel to the points of connection of the other panel, the surge impedances of the first said lines connected to one alternate set of dipoles of one panel being ar-

ranged below last said dipoles to match the parallel impedances of last said dipoles, and the surge impedances of last said lines between adjacent last said dipoles being arranged to match the parallel impedances of those of last said dipoles above said portions.

25. In a turnstile antenna, in combination, a plurality of folded dipoles arranged in crossed relation in two longitudinal panels, the dipoles being spaced apart half a wave length, a plurality of coaxial feeder lines, each feeder line having its inner conductor connected only to similar ends of alternate dipoles of a panel, each pair of coaxial feeder lines thus connected to similar ends of the dipoles of a panel being connected together at points of connection to feed said similar ends in phase, a pair of quarter wave length transformers connected to the points of connection of one panel, a pair of main feeder coaxial lines connected to said transformers, and coaxial lines of an odd number of quarter wave lengths connecting the points of connection of one panel to the points of connection of the other panel, the surge impedances of the coaxial lines of an odd to one alternate set of dipoles of one panel being arranged to match the parallel impedances of the dipoles to which they are connected, the surge impedances of the coaxial lines of an odd number of quarter wave lengths being arranged to match the parallel impedances of the two panels, and the impedances of the quarter wave length coaxial line transformers being arranged to match the impedances of the main feeder coaxial lines to the parallel impedances across the connecting points to which they are connected.

26. In a turnstile antenna, in combination, a plurality of folded dipoles arranged in crossed relation in two longitudinal panels, the dipoles being spaced apart half a wave length, a plurality of coaxial feeder lines, each feeder line having its inner conductor connected only to similar ends of alternate dipoles of a panel, each pair of coaxial feeder lines thus connected to similar ends of the dipoles of a panel being connected together at points of connection to feed said similar ends in phase, a pair of quarter wave length transformers connected to the points of connection of one panel, a pair of main feeder coaxial lines connected to said transformers, and coaxial lines of an odd number of quarter wave lengths connecting the points of connection of one panel to the points of connection of the other panel, the surge impedances of the first said lines connected to one alternate set of dipoles of one panel being arranged below last said dipoles to match the parallel impedances of last said dipoles, and the surge impedances of last said lines between adjacent last said dipoles being arranged to match the parallel impedances of those of last said dipoles above said portions, the surge impedances of the coaxial lines of an odd number of quarter wave lengths being arranged to match the parallel impedances of the two panels, and the impedances of the quarter wave length coaxial line transformers being arranged to match the impedances of the main feeder coaxial lines to the parallel impedances across the connecting points to which they are connected.

27. A feeder system comprising eight coaxial lines, two of said coaxial lines being connected to separate points of connection, and two others of said coaxial lines being connected to another two separate points of connection, a pair of coaxial lines of an odd number of half wave lengths connecting two others of said eight lines to first said

points of connection, another pair of coaxial lines of an odd number of half wave lengths connecting the other two of said eight lines to the other two points of connection, and a pair of coaxial lines of an odd number of quarter wave lengths connecting the two pairs of separate points of connection.

28. A feeder system comprising eight coaxial lines, two of said coaxial lines being connected to two separate points of connection, and two others of said coaxial lines being connected to another two separate points of connection, a pair of half wave length coaxial lines connecting two others of said eight lines to first said points of connection, another pair of half wave length coaxial lines connecting the other two of said eight lines to the other two points of connection, and a pair of quarter wave length coaxial lines connecting the two pairs of separate points of connection.

29. A feeder system comprising eight coaxial lines, two of said coaxial lines being connected to separate points of connection, and two others of said coaxial lines being connected to another two separate points of connection, a pair of coaxial lines of an odd number of half wave lengths connecting two others of said eight lines to first said points of connection, another pair of coaxial lines of an odd number of half wave lengths connecting the other two of said eight lines to the other two points of connection, and a pair of coaxial lines of an odd number of quarter wave lengths connecting the two pairs of separate points of connection, the surge impedances of last said coaxial lines being arranged to match the impedances at said connecting points.

30. A feeder system comprising eight coaxial lines, two of said coaxial lines being connected to two separate points of connection, and two others of said coaxial lines being connected to another two separate points of connection, a pair of half wave length coaxial lines connecting two others of said eight lines to first said points of connection, another pair of half wave length coaxial lines connecting the other two of said eight lines to the other two points of connection, and a pair of quarter wave length coaxial lines connecting the two pairs of separate points of connection, the surge impedances of last said coaxial lines being arranged to match the impedances at said connecting points.

31. A feeder system comprising eight coaxial lines, two of said coaxial lines being connected to separate points of connection, and two others of said coaxial lines being connected to another two separate points of connection, a pair of coaxial lines of an odd number of half wave lengths

connecting two others of said eight lines to first said points of connection, another pair of coaxial lines of an odd number of half wave lengths connecting the other two of said eight lines to the other two points of connection, a pair of coaxial lines of an odd number of quarter wave lengths connecting the two pairs of separate points of connection, the surge impedances of last said coaxial lines being arranged to match the impedances at said connecting points, a pair of main coaxial feeder lines excited in opposite phase, and a pair of quarter wave coaxial line transformers connecting said main lines to a pair of said separate points and providing impedance matching between said lines and said points.

32. A feeder system comprising eight coaxial lines, two of said coaxial lines being connected to two separate points of connection, and two others of said coaxial lines being connected to another two separate points of connection, a pair of half wave length coaxial lines connecting two others of said eight lines to first said points of connection, another pair of half wave length coaxial lines connecting the other two of said eight lines to the other two points of connection, a pair of quarter wave length coaxial lines connecting the two pairs of separate points of connection, the surge impedances of last said coaxial lines being arranged to match the impedances at said connecting points, a pair of main coaxial feeder lines excited in opposite phase, and a pair of quarter wave coaxial line transformers connecting said main lines to a pair of said separate points and providing impedance matching between said lines and said points.

33. In combination, a plurality of parallel folded dipoles, each dipole having a major length, two return bends and two inwardly directed lesser lengths, the return bends of one of said dipoles being directed in one direction around the center of said one dipole and the return bends of an adjacent dipole being directed in the opposite direction around the center of said other dipole.

34. A turnstile antenna comprising a plurality of cross dipoles arranged in two parallel series, a plurality of straight feeder lines connected to said dipoles and a feeder system connected to said straight feeder lines to excite the dipoles of each series in phase and to excite the dipoles of both series in relative phase relationship to create fields which rotate in the same direction at the frequency supplied by the feeder system.

CERTIFICATE OF CORRECTION.

Patent No. 2,338,564.

January 4, 1944.

NATHAN W. ARAM.

It is hereby certified that error appears in the printed specification of the above numbered patent requiring correction as follows: Page 3, first column, line 43, for "regulationship" read --relationship--; line 52, strike out the words "The relationship between the other pair of" and insert instead --The net parallel impedance between the points--; page 4, first column, line 67, before "feeder" strike out "straight" and insert the same after "comprising a" in line 68; page 6, second column, line 24, strike out "coaxial lines of an odd" and insert instead --first said lines connected--; line 28, for "old" read --odd--; and that the said Letters Patent should be read with this correction therein that the same may conform to the record of the case in the Patent Office.

Signed and sealed this 18th day of April, A. D. 1944.

Leslie Frazer

Acting Commissioner of Patents.
